L. GOLDSTEIN.
TURNOVER MACHINE.
APPLICATION FILED JAN. 19, 1921.

Patented June 14, 1921.

Fig. 1.

UNITED STATES PATENT OFFICE.

LOUIS GOLDSTEIN, OF BROOKLYN, NEW YORK.

TURNOVER-MACHINE.

1,381,820.

Specification of Letters Patent. Patented June 14, 1921.

Application filed January 19, 1921. Serial No. 438,431.

To all whom it may concern:

Be it known that I, LOUIS GOLDSTEIN, a citizen of the United States, and a resident of the city of New York, borough of Brooklyn, in the county of Kings and State of New York, have invented a new and Improved Turnover-Machine, of which the following is a full, clear, and exact description.

The object of the invention is to provide a new and improved turnover machine more especially designed for turning over tubular articles notably fur pieces such as fur paws and the like, and without danger of injuring the article during the turning over operation and without requiring the use of a skilled operator. Another object is to facilitate the turning over operation with a view to enable an operator to turn over a large number of articles in a comparatively short time. Another object is to provide a turnover machine which is very simple and durable in construction and not liable to get out of order easily.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a plan view of the improved turnover machine;

Fig. 2 is a sectional side elevation of the same; and

Fig. 3 is a side elevation partly in section of the two rods and showing a tubular piece of fur in clamped position between the rods ready for being turned over.

Two spaced brackets 10 and 11 are fastened by screws or other fastening devices 12 and 13 to a table 14 or other suitable support. The brackets 10 and 11 are rigidly connected with each other by two guide rods 15 on which is mounted to slide a crosshead 16 normally held against the bracket 10 by the action of springs 17 coiled on the guide rods 15 and pressing against the inner face of the crosshead 16. The springs 17 abut against collars 18 adjustably fastened to the guide rods 15 by set screws 19 which regulate the tension of the springs 17. A chain 20 is connected at one end to the under side of the crosshead 16 intermediate the guide

rods 15, and the said chain extends between the said guide rods and passes over a pulley 21 journaled in the bracket 11. The chain after leaving the pulley 21 passes through an opening 22 in the table 14 to connect with a treadle or other actuating device (not shown) for exerting a pull on the chain 20 to move the crosshead 16 from the left to the right on the guide rods 15 and against the tension of the springs 17. On releasing the pull on the chain 20 the springs 17 return the crosshead 16 to normal position against the bracket 10.

On the crosshead 16 is secured a vertically disposed shank 25 of a holder 26 by the use of set screws 27 and in the said holder is secured by a set screw 28 one end of a horizontally disposed rod 30 provided at its free end with a seat or socket 31. A rod 32 is fixed at one end in the bracket 11 by a set screw 33 and this fixed rod 32 has its axis in line with the axis of the rod 30 moving with the crosshead 16. The rod 32 is provided with a reduced shank 34 terminating in a head 35 adapted to coact with the seat 31 to clamp the end of the tubular piece 40 to be turned over in position on the seat 31, as plainly shown in Fig. 3, at the time the tubular piece 40 is in position on the rod 30 and the crosshead 16 with the rod 30 is moved from the left to the right, as previously explained. By reference to the drawings, it will be noticed that the rod 30 is somewhat larger in diameter than the shank 34 to provide a proper clamping seat 31 for coaction with the head 35. In practice, the head 35 and the seat 31 are preferably made spherical and the head 35 is preferably roughened (see Fig. 3) to insure a firm clamping action of the end piece 40 on the seat 31.

The operation is as follows: When the parts are in the position shown in Figs. 1 and 2 then the head 35 and the socket 31 are spaced a short distance apart to permit the operator to slip the piece 40 to be turned over onto the rod 30. When this has been done, the outer open end of the piece 40 is pressed by the operator's fingers into the socket 31 and at the same time the crosshead 16 is moved from the left to the right to cause the head 35 to clamp the inturned end of the piece 40 firmly against the seat 31 (see Fig. 3). The operator now takes hold of the piece 40 and strips the same from the left to the right whereby the piece

40 is turned over on account of its outer end being held clamped in the seat 31 by the head 35. It is understood that in moving the piece 40 from the left to the right 5 it is turned over and stripped onto the shank 34 and the rod 32. When this has been done the operator releases the chain 20 to allow the crosshead 16 to return to its normal position by the action of the spring 10 17 and whereby the rod 30 is moved away from the rod 32 to allow of stripping the turned over piece from the rod 32 at the free end thereof. It is understood that a tubular fur paw can be readily turned over 15 either way, that is, to turn it over when the fur is inside or when the fur is outside.

From the foregoing it will be seen that by the arrangement described the tubular piece can be readily turned over without 20 danger of injuring the article during the turning over operation.

It will also be noticed that an operator can turn over a large number of articles in a comparatively short time.

25 It is expressly understood that the machine is particularly designed for turning over tubular pieces open at both ends such as fur paws.

It is understood that the shank 25 of the 30 holder 26 is vertically adjustable in the crosshead 16 to insure accurate alinement of the rod 30 with the rod 32.

Having thus described my invention, I claim as new and desire to secure by Letters Patent:—

1. A turnover machine for turning over open-ended tubular fur pieces, comprising a fixed rod and a movable rod, one of the rods extending through the open ended tubular piece to be turned over, the axes of the rods being on line and the adjacent ends of the rods having clamping means clamp- 40 ing between them the open end of a tubular piece to allow an operator to strip the tubular piece onto the other rod.

2. A turnover machine for turning over open-ended tubular fur pieces, comprising a rod fixed at one end, and a reduced shank terminating in a head, a movable rod on 50 which is slipped an open ended tubular piece to be turned over, the axes of the rods being

on line, the said movable rod being larger in diameter than the said shank and having its free end provided with a seat onto which the open end of the tubular piece is clamped 55 by the said head, and means actuated by an operator and connected with the said movable rod to move the latter in clamping position relative to the other rod.

3. A turnover machine, comprising a rod 60 fixed at one end and a reduced shank terminating in a head, a movable rod on which is slipped a tubular piece to be turned over, the axes of the rods being on line, the said movable rod being larger in diameter than 65 the said shank and having its free end provided with a seat onto which the end of the tubular piece is clamped by the said head, a crosshead on which the said movable rod is secured, guiding means for the said crosshead to slide on, springs held on the said guiding means and pressing the said crosshead to hold the latter normally in inactive 70 position with its seat spaced from the said head to allow of slipping the tubular piece 75 onto the movable rod, and actuating means under the control of an operator and connected with the said crosshead to move the movable rod into clamping position relative to the head of the said fixed rod. 80

4. A turnover machine comprising a pair of spaced brackets adapted to be attached to a support, guide rods connecting the said brackets with each other, a crosshead slide- 85 able on the said guide rods, springs coiled on the guide rods and pressing the said crosshead to normally hold the same against one of the said brackets, a rod supported at one end on the said crosshead and pro- 90 vided at its other end with a seat, the said rod being adapted to support the tubular piece to be turned over, a rod fixed in the other bracket and having its axis in line with that of the said crosshead rod, the said fixed rod having a reduced shank and a 95 head on the end of the shank and adapted to clamp one end of the piece to be turned over onto the said seat, and actuating means connected with the said crosshead to move the latter and its rod toward the other rod 100 and against the tension of the said springs.

LOUIS GOLDSTEIN.
